Term of patent 14 years

(Cl. D14—3)

FIGURE 1.

FIGURE 2.

FIG. 1 is a rear quarter view in perspective of a bulk load body for a vehicle showing our new design;

FIG. 2 is a side view in elevation thereof the opposite side thereof being the same;

FIG. 3 is a plan view of the body;

FIG. 4 is a view in elevation taken from the front end of the body;

FIG. 5 is a rear view in elevation thereof, with the end gate in open position; and

FIG. 6 is a vertical cross sectional view of the body.

The dominant features of our design reside in the portion shown in full lines.

We claim:

The ornamental design for a bulk load body for a vehicle, as shown and described.
